STORAGE VESSEL

Harry C. Boardman, Chicago, Ill., assignor to
 Chicago Bridge & Iron Company, a corporation
 of Illinois

Application October 6, 1943, Serial No. 505,105

13 Claims. (Cl. 220—71)

1

This invention relates to a storage vessel and more particularly to a storage vessel of large capacity and considerable height.

Storage vessels of this type are customarily made of sheet metal of generally cylindrical form. The sheet metal is of sufficient thickness to withstand the pressure either of the liquid contained within the vessel or of any other internal pressure which may exist. Where this pressure is high, the metal thickness must of course be correspondingly great, and, in storage vessels of large capacity, the thickness tends to increase to amounts which may be undesirable and which are in any event undesirably thick for welding. The present invention provides a structure which is basically cylindrical in form and which requires no more, or at best very little more total metal, than is required with a truly cylindrical vessel, and which requires much less welding.

The invention is illustrated in the drawings, in which Fig. 1 is a partial plan view with the roof removed of the preferred form of the container; Fig. 2 is a sectional elevation taken along the line 2—2 in Fig. 1; Fig. 3 is a similar view of a further modification; Fig. 4 is a fragmentary sectional plan view of a modified form; Fig. 5 is a sectional elevation on line 5—5 of Fig. 4; Fig. 6 is a fragmentary plan view of another modified structure; Fig. 7 is a section taken along the line 7—7 in Fig. 6; and Fig. 8 is a partial plan view with the roof removed of another modified structure.

The container 10 comprises a sheet metal shell 11 in the form of a plurality of circular segments 12 made up of individual sheet metal plates arranged in horizontal courses or rows. It is understood that the use of such courses is standard practice in the construction of storage vessels, each successive course being of thinner metal than the preceding lower course.

It will be noted that the intersections 14 and 14a of adjacent circular segments lie on the periphery of the imaginary cylinder 15 shown in dotted lines in Figure 1. Vertical radial diaphragms 16 are provided at the intersections 14 and 14a, etc., extending either inwardly or outwardly to or away from the axis 17 of the cylinder 15. These diaphragms are arranged in courses in the same manner as the plates in the circular segments 12. They are connected by tie members 18 which may be either sheet metal, rods or the like. The thickness of the diaphragms 16 and the tie members 18 in each course may be calculated readily in accordance with known engineering procedure.

2

It is not essential that the edges of adjacent courses of diaphragms or tie bars be connected. For example, as shown in Figure 2, the edge 20 between the diaphragms 16 and 16a is left free, as is the edge 21 between the diaphragms 16a and 16b. Similarly the edges 22 and 23 between tie bars 18 and 18a, and 18a and 18b, respectively, are preferably left free.

In the modification shown in Fig. 3, the diaphragms 160 are extended outwardly beyond the circular segments 120 and are then connected by the tie bars 180. In this modification the tie bars 180 may be suitably connected to the mid-sections of the circular segments to provide a bracing against twisting. Post 121 may also be provided at the diaphragms 160 if desired. The form of structure shown in Fig. 3 is particularly suitable where a floating roof 122 is to be employed.

20 It is of course not essential that the radial diaphragms in all courses be of the same length and in fact it may be desirable in some cases to eliminate radial diaphragms in the upper courses entirely, as shown in Figs. 6 and 7. This modification may be employed where the thickness of the metal becomes less than it is desired to handle or where additional thinness is either undesirable or unimportant.

25 The length of the radial diaphragms is theoretically unimportant, since the amount of metal required is the same. However, it is of considerable importance that they be neither too short nor too long. For example, it is preferred that the diaphragm be at least sufficiently long to permit access to the sectors 25 bounded by any pair of diaphragms, the tie bar, and the outer wall 12. It is also preferred that the metal in the diaphragms be thick enough for practicable handling and to withstand ordinary corrosive influences.

30 It may readily be shown that the amount of metal required for the structure shown in Fig. 1 is identical in weight with that required for a circular cylinder of the same height and capacity. This relationship holds true for radial diaphragms of zero length up to the radius "R" of the cylinder 15. It is not quite true for the form shown in Fig. 3, as slightly more metal is required.

35 While the amount of metal required is the same, the thickness of metal employed in the wall sections may be greatly reduced. For example, in the structure shown in Figs. 6 and 7, a storage tank of 400,000 barrels capacity in cylindrical form, and 40 ft. in height, would have a radius of about 134 ft., when using a scalloped

wall intersecting on a cylinder having a radius of 133 ft. but having a radius of curvature of 67 ft., the wall thickness in each of the courses 30, 31 and 32 may be reduced approximately 50%.

The bottom 40 may be of any suitable form. It is illustrated as a common sheet metal bottom. The lower diaphragm 16 may, if desired, have its bottom edge welded to the bottom 40 of the tank, and the lower portion of the tie bar 18 may then be omitted since the bottom 40 will act in its place.

The top 50 of the tank may be of any suitable type although, if it is to be a floating roof 122 as shown in Fig. 3, the outer segmental structure shown in Fig. 3 should be employed.

The amount of welding required is greatly reduced as compared with an ordinary cylindrical tank of the same capacity and height. The amount of welding increases more than proportionately with the thickness of the metal and generally approaches the square of the ratio. In the present structure the only welding required is the outer shell, and the welding of the edges of the diaphragms to the outer shell and to the tie members. In the structure shown in Figs. 6 and 7 it is also necessary to include a plate 60 to close the residual segments above the course 32. In any event, however, the total welding is very considerably less than would be required of the cylindrical form.

It will be observed that the tie members form an inner shell. This inner shell does not, however, need to be complete, and the radial diaphragms may be tapered to a relatively narrow inner shell member. Furthermore a series of inner shell members may be provided as illustrated in Fig. 8, wherein radial diaphragms 161 are connected by inner shell members 181 and 182. Such a plurality of structures may be employed where it is desired to have no metal thicker than a predetermined maximum.

The circular segments or scallops need not of course be of the same radius of curvature in the various courses. Figs. 6 and 7 are modifications of this type in which the fourth and fifth courses 33 and 34 have a radius of curvature equal to that of the cylinder. If the radius of curvature in any course is different from the radius in any other course, suitable plates must be used to cover the resulting openings between the courses.

The bottom course of the inner shell members should not be fastened to the bottom of the tank, nor should the top course of the inner shell members be fastened to the roof of the tank.

By selecting the number of cusps or segments and adjusting the area and length of the diaphragms, it is possible to make all the metal in the tank in any given course of equal thickness.

The modifications shown in Figs. 4 and 5 is a deviation in which the vessel 190 has an outer shell made up of a series of conical scallops 195 connected at their intersections by radial diaphragms 196 which are in turn held by tie members 191. The radius of curvature of the scallops is varied from top to bottom of the container. For example, as shown, the top of the vessel is a circle of the same radius of curvature as the distance between the center of the container and the center of any scallop. At the bottom, however, the radius of curvature is markedly less, for example, half as much as at the top. In any horizontal section, the scallops intersect on the circle and the summation of these circles forms an inverted cone. The cone, however, is usually substantially cylindrical in form.

The foregoing detailed description has been given for clearness of understanding only, and no unnecessary limitations should be understood therefrom.

5. What I claim as new and desire to secure by Letters Patent is:

1. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a predetermined series of horizontal superimposed circles, vertical radial diaphragms extending from the vertical intersections of the segments along radii of the said circles, and tie members connecting the diaphragms, the radial diaphragms in each course being substantially unconnected to adjacent radial diaphragms.
2. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a predetermined series of horizontal superimposed circles, vertical radial diaphragms extending from the vertical intersections of the segments along radii of the said circles, and tie members connecting the diaphragms, the radial diaphragms in each course being substantially unconnected to adjacent radial diaphragms.
3. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a predetermined series of horizontal superimposed circles, vertical radial diaphragms extending inwardly from the vertical intersections of the segments along radii of the said circles, and inner shell members connecting the diaphragms, the radial diaphragms in each course being substantially unconnected to adjacent radial diaphragms.
4. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a predetermined series of horizontal superimposed circles, vertical radial diaphragms extending from the vertical intersections of the segments along radii of the said circles, and tie members connecting the diaphragms, the upper courses of said vessel being cylindrical, and there being cover plates connecting the lower edge of the lowest cylindrical course with the upper edge of the upper course of circular segments.
5. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a circle, vertical radial diaphragms extending from the vertical intersections of the segments along radii of the circle, and tie members connecting the diaphragms, the radial diaphragms in each course being substantially unconnected to adjacent courses of radial diaphragms.
6. In a storage vessel of generally cylindrical

shape, a sheet metal shell comprising a series of horizontal courses of circular segments with their concave surfaces facing inwardly and vertically intersecting at an angle of less than 180° with adjacent segments on the periphery of a circle, vertical radial diaphragms extending from the vertical intersections of the segments along radii of the circle, and tie members connecting the diaphragms, the radial diaphragms in each course being substantially unconnected to adjacent courses of radial diaphragms, and tie members in each course being substantially unconnected to tie members in adjacent courses.

7. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a circle, vertical radial diaphragms extending inwardly from the vertical intersections of the segments along radii of the circle, and inner shell members connecting the diaphragms, the radial diaphragms in each course being substantially unconnected to adjacent courses of radial diaphragms.

8. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a circle, vertical radial diaphragms extending from the vertical intersections of the segments along radii of the circle, and tie members connecting the diaphragms, the upper courses of said vessel being cylindrical, and there being cover plates connecting the lower edge of the lowest cylindrical course with the upper edge of the upper course of circular segments.

9. In a storage vessel, a sheet metal shell comprising a series of horizontal courses of scallops formed of circular segments on any horizontal cross-section, said scallops vertically intersecting with adjacent scallops to form a complete shell, vertical diaphragms extending inwardly from the intersection of each pair of scallops, and tie members connecting the diaphragms, the diaphragms in each course being substantially unconnected to diaphragms in adjacent courses.

10. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a circle, vertical radial diaphragms extending from the vertical intersections of the segments along radii of the circle, and tie members connecting the diaphragms, the tie members in each course being substantially unconnected to adjacent courses of tie members.

11. In a storage vessel of generally cylindrical shape, a sheet metal shell comprising a series of

horizontal courses of circular segments with their concave surfaces facing inwardly and vertically intersecting at an angle of less than 180° with adjacent segments on the periphery of a predetermined cylinder, vertical radial diaphragms extending from the vertical intersections of the segments along radii of the cylinder, and tie members connecting the diaphragms, the radial diaphragms and tie members in each course being substantially unconnected to adjacent radial diaphragms and tie members, respectively.

12. In a storage vessel of generally cylindrical shape, a sheet metal shell comprising a series of horizontal courses of circular segments with their concave surfaces facing inwardly and vertically intersecting at an angle of less than 180° with adjacent segments on the periphery of a predetermined cylinder, vertical radial diaphragms extending from the vertical intersections of the segments along radii of the cylinder, at least one sheet metal face including a bottom connecting at least one of the end courses of circular segments, and tie members connecting the diaphragms, the radial diaphragms and tie members in each course being substantially unconnected to adjacent radial diaphragms and tie members, respectively, and an end course of said radial diaphragms being connected to the adjacent end face of the storage vessel.

13. In a storage vessel, a sheet metal shell comprising a series of horizontal courses of scallops formed of circular segments on any horizontal cross section, said scallops vertically intersecting with adjacent segments to form a complete shell, vertical diaphragms extending inwardly from the intersection of each pair of scallops, and tie members connecting the diaphragms, the tie members in each course being substantially unconnected to adjacent courses of tie members.
